UNITED STATES PATENT OFFICE.

SWAN A. NELSON, OF STROMSBURG, NEBRASKA.

ARTIFICIAL ARM.

1,285,326.

Specification of Letters Patent. Patented Nov. 19, 1918.

Application filed August 27, 1917. Serial No. 188,348.

To all whom it may concern:

Be it known that I, SWAN A. NELSON, a citizen of the United States, residing at Stromsburg, in the county of Polk and State 5 of Nebraska, have invented certain new and useful Improvements in Artificial Arms, of which the following is a specification.

This invention relates to improvements in artificial limbs and more particularly to an 0 artificial arm adapted for attachment to the shoulder of the user. The limb comprises an upper arm to which a forearm is adjustably secured, means being provided for locking the forearm in any adjusted position 5 and for instantly releasing the forearm from such position when desired, said means being operable from the shoulder. Further, the limb comprises a hand with integral fingers, said hand and fingers being stationary 10 with relation to said forearm, said hand being provided with a movable thumb controlled by a slight movement of the wearer's chest about which a portion of the supporting harness extends, connection between the 15 harness and thumb being provided. More specifically the invention consists in the combination and arrangement of parts to be hereinafter fully described, pointed out in the appended claims and illustrated in the 20 accompanying drawings which form a part of this specification and in which—

Figure 1 is a side elevation of my artificial limb, the dotted lines showing the forearm in raised position.

Fig. 2 is a fragmentary plan view of the 5 arm, the elbow joint being exposed to afford a better illustration.

Fig. 3 is a longitudinal sectional view through Fig. 2.

Fig. 4 is a fragmentary sectional view of the 10 lower part of the limb showing the operating mechanism for the thumb.

Fig. 5 is a cross section taken on line 5—5 of Fig. 2.

Fig. 6 is a cross section on line 6—6 of Fig. 2 with some parts removed.

Fig. 7 is a plan view of Fig. 4.

Like reference characters denote corresponding parts throughout the several views.

My invention includes an upper arm having a core 1, preferably of wood or cork and provided with a leather covering 2 which is open in the front and provided with eyelets 3 by means of which, and the cord 4, it may 5 be laced shut. The upper end of the covering 2 is formed with ears 5 to which the

harness 6 is secured, said harness being adapted to pass across the back and chest of the user and under the arm upon the opposite side of the body to which my arm is attached. A brace-strap 7 connects the front of the covering 2 with one ear 5 and the harness 6. The said core 1 extends beyond the lower termination of the covering 2 and is bifurcated at its lower end and transversely through said bifurcated end the elbow pivot 8 extends, said pivot connecting the forearm 9 to the upper arm, the ends of said elbow pivot connecting the longitudinal bands 10 of the upper arm, pivotally, with 70 the longitudinal bands 11 of the forearm. The upper termination of the forearm is hollow and open to permit access to its interior, the open portion of the forearm as well as the bifurcated portion of the upper 75 arm being covered by a flexible sheet 12.

The forearm terminates in a hand 13, the fingers 14 of which are relatively stationary, said hand being provided with a thumb 15. A spring 16 connects the wall 17 of the 80 thumb with the post 23 to yieldingly retain the thumb in frictional engagement with a finger 14.

The pivoted end of the thumb is provided with a toothed segment 20 in mesh with a 85 toothed segment 21 formed terminally of a link 22 connected by pivot 23 to a stay-plate 24 arranged in the hand 13, said stay plate being connected by screws 25 passing to the hand. The said link 22 is formed with a 90 perforation 26 in one end to permit its engagement by a link 27 to which a cord 28 is secured, said cord passing through the forearm and over a sleeve or roller 29 arranged upon a shaft 30, said sleeve 29 also carrying 95 a disk 31 which serves as a guide for the cord 28 to limit its lateral movement within the forearm. Beyond the sleeve 29 the cord 28 passes over a guide roller 32 and through the bifurcated end of a fork 33, said fork- 100 end carrying the shaft 34 of the said guide roller 32 and said fork being secured by fastening means 35 to the core 1. The cord 28 extends over a guide roller 36 of roller-shaft 37 disposed in a recess 38 formed in 105 the core 1, said roller-shaft being journaled in the said core, and beyond said roller the cord passes out between the sheet 12 and covering 2 and over a guide-roller 39, carried by said covering, to the harness 6 to 110 which it is secured.

Adjacent the inner face of one prong of

the bifurcated end of the core 1 I provide a sheave 40 which is centered but loose upon the elbow pivot 8, said sheave being carried by an arm 41 fast to the shaft 30 and said 5 sheave being formed with one lateral flange 42 that extends beyond the periphery of said sheave and that spaces said member away from the adjacent prong of the core 1. The said sheave, further, is formed with an integral toothed segment 43 of smaller diameter than the sheave itself, said segment being adapted normally for locking engagement with a dog 44 fulcrumed upon the elbow pivot 8, said dog being yieldingly retained in engagement with the segment 43 by means of an expansion spring 45 arranged upon the shaft 8 and abutting said dog and the core 1. The dog is formed with the ears 46 to which the strap 47 is secured 10 that extends out through an opening 48, in which is arranged a pulley 48', in the core 1 and through a guide ring 49, carried by the covering 2, to the harness 6 to which it is secured.

25 A hook 50 fast to the shaft 30 is engaged by a cord 51 which passes over the sheave 40 and out through a perforation 51' in which is arranged a roller 51" in the core 1 and up through guide-loops 52 to the harness, one guide-loop-strap being connected by a spring 53 to the brace-strap 7. To operate the thumb 15 against the tension of its spring the operator expands his chest to cause a pull upon the strap 28 which will 30 move the link 22 upon its pivot and so move the thumb away from the fingers 14. When the tension upon the strap 28 is relaxed the spring will again move the thumb into frictional engagement with the fingers. To 35 move the forearm upon the elbow pivot the operator raises his shoulder adjacent the limb to cause a pull upon the strap 47, the strap being adjusted to closely fit the shoulder, which will withdraw the dog 44 from 40 locking engagement with the segment 43, a further shoulder movement will now cause the strap 51 to raise or lower the forearm as desired. A forward movement of the shoulder will drop the forearm and a back 45 movement of the shoulder will raise the forearm and when the shoulder is lowered to normal position the spring 45 will force the dog into engagement with the segment 43 again locking the arm in adjusted position. The first shoulder movement is always 50 an upward movement to effect release of the dog from its segment and the second shoulder movement is a forward or backward movement to lower or raise the forearm 55 as desired. With a little practice the user will become adept in effecting the arm and thumb movements described.

What is claimed is:—

1. In an artificial arm including a hand 65 member, an arm-supporting harness adapt-

ed to be fitted to and movable with a person's shoulders and chest, a thumb pivotally supported by said hand, means connecting said thumb and hand for yieldingly retaining the free end of said thumb in frictional engagement with one of the fingers of said hand, a control lever for said thumb pivotally secured to said hand, and flexible means connecting said lever and the said harness whereby movement of the latter due to expansion and contraction of a person's chest 70 will operate to actuate said lever.

2. In an artificial arm including a hand member, an arm-supporting harness adapted to be fitted to and movable with a person's shoulders and chest, a thumb pivotally secured to said hand, a toothed segment terminating said thumb, a spring connecting said thumb and hand for yieldingly retaining said thumb with frictional engagement 80 with one of the fingers of said hand, a toothed lever pivotally secured to said hand and in operative engagement with said segment, and flexible connection between said lever and the said harness whereby movement of the latter due to expansion and contraction of a person's chest 85 will actuate said lever.

3. In an artificial arm, an upper arm, a supporting harness for said upper arm 95 adapted to be fitted to and movable with a person's shoulders and chest, a forearm, an elbow pivot connecting said upper arm and forearm, a toothed segment movably centered upon said elbow pivot, a dog carried 100 upon said elbow pivot for releasable locking engagement with said segment, control means for said dog connecting the same and said harness, and means connecting said forearm and harness whereby movement of the 105 latter may be transmitted to said forearm.

4. In an artificial arm, an upper arm, a supporting harness for said upper arm adapted to be fitted to and movable with a person's shoulders and chest, a forearm, an 110 elbow pivot connecting said upper arm and forearm, a transverse shaft carried by said forearm, a toothed segment carried by said transverse shaft and associated with said elbow pivot, a dog carried upon said elbow 115 pivot for releasable locking engagement with said segment, control means for said dog connecting the same and said harness, and flexible means connecting said forearm and harness whereby movement of the latter 120 may be transmitted to the former.

5. In an artificial arm, an upper arm, a supporting harness for said upper arm adapted to be fitted to and movable with a person's shoulders and chest, a forearm, an 125 elbow pivot connecting said upper arm and forearm, a transverse shaft carried by said forearm, a sheave operatively supported by said transverse shaft and associated with said elbow pivot, a toothed segment integral 130

with said sheave, a dog carried by said elbow pivot, for releasable locking engagement with said segment, and flexible means for connecting said harness and transverse shaft 5 whereby movement of said harness may be transmitted to said forearm.

In testimony that I claim the foregoing

as my own I have hereto affixed my signature in the presence of two subscribing witnesses.

SWAN A. NELSON.
